UNITED STATES PATENT OFFICE

2,234,812

FOUNTAIN PEN

John A. Snodgrass, Prescott, Ark.

Application August 15, 1940, Serial No. 352,683

4 Claims. (Cl. 120—44)

This invention relates to fountain pens and in such connection it relates more particularly to the novel construction and arrangement of the parts thereof.

5 The present invention relates further to Letters Patent No. 2,149,557, granted to the applicant on March 7, 1939, and has for its general object the provision of an improved pen point which causes the ink to be conducted from the barrel of

10 the pen in a novel and unique manner.

Another object of the present invention is to improve the writing point or end of the pen nibs which contact the writing material by the provision of a circular channel in the end of the pen 15 nibs which channel communicates with the customary or regular slit or channel already in pen points.

A further object of the invention is to provide a modification of the circular channel referred 20 to above, and to eliminate the wick for the ink feed, and yet retain the structure of the pen body in all other essential parts.

With the foregoing objects in view, the invention will be clearly understood from a perusal of 25 the following detailed description, taken in connection with the accompanying drawing, and in the drawing:

Figure 1 is a partial longitudinal sectional view 30 of a fountain pen embodying the invention;

Figure 2 is a partial longitudinal sectional view of Figure 1, the view being taken along the line 2—2 of said figure;

Figure 3 is a cross-sectional view of Figure 1, the view being had along the line 3—3 thereof;

Figure 4 is a cross-sectional view of Figure 1, the view being had along the line 4—4 thereof;

Figure 5 is an exaggerated side elevational view 35 of the pen point or writing element of the pen, per se;

Figure 6 is an exaggerated view of the writing end of the pen point, showing the circular channel and the writing position of the pen point; Figure 7 being an end view of Figure 6;

Figure 8 is an exaggerated, fragmentary top 40 plan view of a modified form of the writing element of the pen; Figure 9 being an end view of Figure 8; and

Figure 10 is an end view of another modified form of the writing element.

50 Referring in detail to the drawing, wherein like parts will be designated by like numerals and letters, 1 indicates the barrel of the pen body, which may be made of any suitable material.

Fastened in the opposite end of the barrel is a 55 plug 3 and over this plug is secured a nipple 4.

While the plug 3 and the nipple 4 are connected by threads as shown, these parts may be engaged by slipping one over the other without the use of threads, and similarly the inner end of the plug 3 may be slipped inside the barrel 1. The plug 5 5 includes a tongue-like extension member 5 which has a channel 6 for conducting the ink from the barrel 1 to the pen nibs or writing element.

The nipple 4 has permanently secured on its 10 lower end a piece of metal 7 for the purpose of strengthening the pen (and also to give the pen a modern stream-like appearance), similar to the metal part on the lower end of a mechanical pencil. This piece of metal is just large enough 15 to permit the pen point to pass through without binding or wedging when removing or replacing the nipple 4 on the plug 3. The arrangement of these parts, however, prevents any play between the pen point or pen nibs 8 and the metal point 20 or element 7. This form of construction prevents a light weight gold point pen from spreading or bending out of shape when the pen is used, therefore this point will be as strong or stronger than the heavy weight gold pen points used in 25 other types of fountain pens, and is strong enough to make carbon copies, which feature is very desirable.

It will be noted that and as in the patent referred to above the tongue-like extension member 30 5 is arranged eccentrically or off-center, so that the pen point or the writing element is on a line centrally of the fountain pen structure.

The particular object of the present invention is to provide an improved writing element or pen 35 point, such as are shown in Figures 2, 5, 6, and 7 to 10 inclusive. In this construction of improved writing element the body 9 of the element fits over and is supported on the tapered, plug extension member 5 and the nibs 8 of the writing element 40 are cylindrical from the point B to the rounded writing point 14, but square in cross-section at 8—a where the nibs pass through the opening 10 in the metal end piece 7. This square portion prevents ink in the channel 11 from touching the 45 piece 7 and thus prevents capillary attraction between the ink channel and the piece 7. The cylindrical portions of the pen nibs are indicated at 12.

Figures 6 and 7 show the rounded writing point 50 of the writing element or pen point, the same being indicated at 14, and that there is formed in the rounded part a circular channel 15, which channel is in fact a continuation of the channel 11. In this arrangement it will be seen that 55

the ink does not flow to the extreme end or the rounded end of the pen point, but flows around the circular channel. This brings the ink onto the writing material or paper P and allows the 5 ink to flow evenly all around the pen point. Figure 6 also shows the angle or writing position of the pen. It will be noted that the rounded end of the pen point does not extend beyond the axial line or outer circumference of the pen nibs as 10 in the former ball point formation in the patent referred to.

In Figures 8, 9 and 10 are shown modifications of the writing end of the pen point. Thus in Figures 8 and 9, instead of the circular channel 15, 15 the rounded end 14 is provided with a straight slit or channel 15-a across the rounded portion. In Figure 10 and in addition to one channel or slit there are provided two slits 15-b at right angles to each other and these modified forms of 20 the slit or channel communicate with the customary ink channel 11 in the pen.

Openings A in the nipple 4 and in a closure nipple or cap 16 provide means for air entrance into the pen.

25 The pen may be filled by a filling device if such is used by unscrewing the nipple 4 from the plug 3, placing the pen point in the ink supply and using the filling device similarly to the manner employed in other fountain pens. If no filling device is used, the nipple 4 is unscrewed from the plug 30 3, the plug is removed from the barrel and the ink well or barrel is filled with an ordinary medicine dropper. The outer cap or nipple 16 is of course removed during the process of filling.

35 From the foregoing it will be apparent that the invention provides an improved fountain pen, especially the writing element thereof and which may be utilized as set out above. The invention, however, may be modified to some extent in keeping with the spirit thereof and which would be 40 within the scope of the appended claims.

What is claimed as new is:

1. A fountain pen comprising an ink barrel, a plug member secured to the lower end of the

barrel, said plug member having a tongue-like extension member disposed off-center or eccentrically of the plug member, and a recess in the plug member for seating a pen nib, said fountain pen including a tapered nipple secured over the 5 said plug member, said tapered nipple having a piece of metal forming its lower end and provided with an aperture through which only the writing point of the pen extends, a tapered closure nipple engaged on the lower end of the barrel, apertures 10 in the tapered closure nipple and said plug nipple for air entrance; said pen nib having a rounded writing point with a circular channel on the writing point, said channel communicating with the regular slit or channel in the pen point or writing 15 element of the pen.

2. A fountain pen as claimed in claim 1, said writing element or pen point of the pen having cylindrical nibs with a rounded end termination which contacts with the writing material, said 20 terminal or writing point of the pen having a circular slit or channel disposed inwardly a slight distance from the writing point of the pen and communicating with the regular or customary slit or channel in the pen point or writing element.

3. A fountain pen as claimed in claim 1, said writing element or pen point of the pen having cylindrical nibs and a rounded end termination which contacts with the paper, the nibs including a square portion in cross-section intermediate the cylindrical portions of the pen nibs at the place where the nibs pass through the opening in said nipple on the plug to prevent capillary attraction of the ink between the nibs and the 30 nipple opening.

4. A fountain pen as claimed in claim 1, said writing element or pen point of the pen having cylindrical nibs with a squared central portion and a rounded writing terminal paper contact point, said rounded point including a channel or channels across the rounded point.

JOHN A. SNODGRASS.
